UNITED STATES PATENT OFFICE.

JOHN THOMAS SEMMENS, OF BALD MOUNTAIN, COLORADO.

CROSS-HEAD FOR MINE-SHAFTS.

SPECIFICATION forming part of Letters Patent No. 668,464, dated February 19, 1901.

Application filed November 3, 1900. Serial No. 35,379. (No model.)

To all whom it may concern:

Be it known that I, JOHN THOMAS SEMMENS, a citizen of the United States, and a resident of Bald Mountain, in the county of Gilpin and State of Colorado, have invented a new and Improved Cross-Head for Mine-Shafts, of which the following is a full, clear, and exact description.

The invention relates to mining machinery; and its object is to provide a new and improved cross-head for mine-shafts arranged to automatically and securely lock the cross-head to the hoisting-cable during the ascent or descent of the cross-head in its guideways and to automatically unlock the cross-head from the cable at the time the cross-head reaches a lowermost position to permit the hoisting-cable and its bucket to descend farther in the mine-shaft.

The invention consists of novel features and parts and combinations of the same, as will be fully described hereinafter and then pointed out in the claim.

A practical embodiment of the invention is represented in the accompanying drawings, forming a part of this specification, in which similar characters of reference indicate corresponding parts in all the views.

Figure 1 is a side elevation of the improvement as applied and with the cross-head resting at the lower ends of the guideways. Fig. 2 is a like view of the same with the cross-head locked to the hoisting-cable; and Fig. 3 is an enlarged sectional plan view of the locking device for locking the cross-head to the cable, the section being on the line 3-3 in Fig. 2.

The cross-head A is mounted to travel in the usual guideways B, arranged in the mine-shaft, and through openings in said cross-head extends a hoisting-cable C, supporting at its lower end a hoisting-bucket D, as is plainly indicated in the drawings. On the hoisting-cable C, at or near the lower end thereof, is clamped or otherwise secured a head E, adapted to be engaged by locking-bars F, mounted to slide in suitable bearings G on the cross-head A, said locking-bars F serving to lock the cross-head A to the cable C by the locking-bars F engaging a reduced portion E' below the conical top E² of the

head E. (See Figs. 2 and 3.) The locking-bars F are pivotally connected at their outer ends with tripping-levers H, fulcrumed on the cross-head A and pressed on by springs I for normally holding said tripping-levers H in the position shown in Fig. 2. The lower curved ends of the tripping-levers H are adapted to engage stops J, secured to the guideways B, at or near the lower ends thereof, said stops forming in addition a rest for the said cross-head A when the latter moves into a lowermost position. (See Fig. 1.) When the cross-head A descends and moves into a lowermost position, the levers F receive a swinging motion by coming in contact with the stops J, so that said levers H move the locking-bars F outward out of engagement with the head E and unlock or disconnect the head, and consequently the cable C, from the cross-head A to permit the hoisting-cable and the bucket D to descend farther in the mine. When the bucket D has been filled and the cable C is caused to ascend, then the head E, with its base E³, moves in engagement with the under side of the cross-head A, so that the latter moves upward with the hoisting-cable, and in doing so the levers H are moved out of engagement with the stops J and the springs I return the levers and locking-bars F to their former position—that is, the inner ends of the locking-bars again engage the reduced portion E' of the head E and lock the cross-head A to said head E, and consequently to the cable C. Thus during the ascent or descent of the cable C the cross-head A is securely locked to the cable until the cross-head reaches a lowermost position—that is, is seated on the stops J—when the cross-head becomes unlocked from the cable and the latter and its bucket are free to descend farther in the mine-shaft. By this arrangement the cross-head A is not liable to become accidentally detached from the cable and drop into the mine-shaft, and thereby cause injury to workmen and to the machinery.

Having thus fully described my invention, I claim as new and desire to secure by Letters Patent—

The combination with a hoisting-cable and a head thereon, of a cross-head, locking-bars

mounted to slide on said cross-head and adapted to engage said cable-head, spring-pressed levers fulcrumed on said cross-head and connected with said locking-bars, and 5 stops adapted to be engaged by said levers at the time the cross-head reaches a lower-most position in the mine-shaft, as set forth.

In testimony whereof I have signed my name to this specification in the presence of two subscribing witnesses.

JOHN THOMAS SEMMENS.
